Strong and Strong

UNITED STATES PATENT OFFICE.

CHARLES E. BENNETT, OF DECATUR, GEORGIA, ASSIGNOR TO BALT MANUFACTURING COMPANY, OF ATLANTA, GEORGIA, A CORPORATION OF GEORGIA.

ARC GAP.

Application filed April 1, 1921. Serial No. 457,638.

To all whom it may concern:

Be it known that I, CHARLES E. BENNETT, a citizen of the United States of America, residing at Decatur, in the county of De Kalb and State of Georgia, have invented certain new and useful Improvements in Arc Gaps, of which the following is a specification.

My invention relates to arc gaps, and particularly to improved gap terminals.

As pointed out in my copending application Serial No. 402,569, filed August 10, 1920, patented January 1, 1924, No. 1,479,693, of which the present application is in part 15 a continuation, large and small gap terminals present different phenomena on arc formation. Between needle terminals, or approximations thereto, corona phenomena occur preceding an actual arc-over. This 20 delays the discharge across the gap. On the other hand, between large terminals, such as sphere terminals, the arc-over is immediate without preliminary corona formation. There is consequently no delay in the discharge across the gap.

It is also a recognized fact that sphere terminals of larger size may be spaced closer together than like terminals of smaller size at the same gap resistance or "rating."

30 In protective ground connections for high voltage lines, it is desirable to provide gap terminals which, although exposed to the elements, will operate with practical uniformity under dry and wet weather conditions. The presence of moisture, such as heavy fog or rain, however, materially lowers the gap resistance, thus ordinarily necessitating a greater spacing between the exposed terminals than is desirable, since 35 this additional spacing between the terminals renders the gap less sensitive to surges under dry weather conditions.

Among the greatest dangers to equipment on power-line installations, are high frequency currents; that is to say currents characterized by "steep wave front." Unless 45 such a current is discharged at once before it reaches equipment, such as transformers, the latter are likely to be burned out and rendered useless. These currents may be imposed upon the line at any time, either under wet or dry conditions.

The object of the present invention is to provide gap terminals of a construction such 50 that they discharge with substantial uni-

formity under wet and dry conditions at the gap, whether the dangerous current imposed upon the line is of either high or low frequency. While the construction shown combines these characteristics, they are not necessarily interdependent since the means employed to effect prompt discharge of high-frequency current may be utilized to advantage without reference to the means by which the lowered resistance of the gap under 60 moisture conditions is compensated. The latter feature alone forms the subject of my earlier application, Serial No. 384,221, filed May 25, 1920 (Patent No. 1,479,692, January 1, 1924), and is therefore not specifically 65 claimed herein.

In the accompanying drawings—

Fig. 1 is a diagram of an illustrative installation in which gap terminals of the present type may be used to advantage;

Fig. 2 is a side elevation of the terminals alone, drawn to a large scale and indicating diagrammatically the electrostatic flux field formed between the terminals by the low-frequency current;

Fig. 3 is a similar view indicating diagrammatically the flux field between the terminals under the influence of high-frequency current;

Figs. 4, 5 and 6 are vertical sections 85 through terminals of various constructions in which my invention is variously embodied.

The installation shown in Fig. 1 represents a power line 10 having a ground connection 11, in which is arranged a gap 12 and an arrester 13 of any suitable sort for breaking the ground connection 14 after the excessive current has been drained from the line. The terminals of the gap 12 are illustrated on a larger scale in Figs. 2 and 3. As here shown, 90 each terminal comprises a metallic button 15 (preferably a segment of a sphere) directly connected to the ground line. Surrounding the button is a disk 16 of insulation, preferably of moisture-absorbent material, such as lava, porous porcelain, or other suitable material. Carried by the disk 16 is a metallic ring 17 forming the periphery of the disk and spaced thereby from the conductor 11 and button 15. Mounted on the line 11 and 95 spaced slightly from the ring 17 is a metal plate 18.

The spacing between the buttons 15 of the opposed terminals is such that under normal line conditions the resistance of the gap is 110

sufficient to prevent discharge across the same to ground. Should a surge occur at normal line frequency, however, this resistance is overcome and the current jumps the 5 gap and is drained from the line through the ground connection 11. The size of the terminals may vary with the normal current carried by the line 10. The diameter of the buttons 15 is such, however, that on a surge 10 at line frequency the arc-over may be preceded by slight corona formation with resultant lag in the discharge. This occasions no danger to equipment so long as the surge is of low frequency since the duration of the 15 corona phenomenon is not long enough to permit the surge current to reach the protected equipment before the arc forms and the line is drained to ground.

When a high-frequency current, however, 20 is imposed upon the line, such a corona lag in the formation of the arc is dangerous to the equipment. A high-speed discharge is essential to the effectiveness of the protective ground line. Such high-speed discharge 25 is attained by the present invention. In the terminals of Figs. 2 and 3, it results from the presence of the metallic ring 17 surrounding the button 15, especially when combined with the associated metal plate 30 18. Effective results are secured without the plate 18, as pointed out in my application Serial No. 402,569, now Patent No. 1,479, 35 693, but I have found that the plate materially accentuates the condenser action of the ring 17, and I therefore prefer to combine the two in the manner indicated, for best results. The effect of the ring 17 under the influence of high-frequency current 40 is to greatly enlarge the electrostatic flux field between the terminals. Under the influence of low-frequency surges the field is practically restricted to a limited area 19, diagrammatically indicated in Fig. 2. Under the influence of high-frequency currents, 45 the condenser action of the ring greatly expands this field, diagrammatically indicated at 20 in Fig. 3. The plate 18 accentuates this condenser action, the lines of force being indicated diagrammatically at 21. With 50 this greatly enlarged and uniform flux field there is no corona formation, and no lag in the arc-over. The high-frequency current is therefore discharged with high speed across the gap, without hesitation or possibility of the current reaching the protected equipment.

I have found, furthermore, that the effect of the plate 18 upon the flux field 20 between the terminals, varies with the spacing 60 of the plate from the ring 17. Thus, by arranging the plate closer to the ring its effect appears to be to expand the field 20 and to render the distribution of the lines of force more uniform, as indicated in Fig. 65 3; whereas by moving the plate further

away from the ring the flux field is not so greatly spread out, so to speak. The differences in the flux field resulting from adjustment of the plate toward or from the ring 17, vary the speed of the gap, and it 70 is thus possible to regulate the gap action with reference to definite conditions of line operation—in other words, to calibrate the gap to the line. This is particularly desirable from a practical standpoint, since the terminal construction may be made standard (within certain limits), and the speed of the gap regulated by the adjustment of the plate toward or from the ring. The means for securing the plate in adjusted position may be 75 of any suitable character—for example, a set screw X passing through the hub Y of the plate and engaging the rod 11.

While I have shown my preferred construction in Figs. 2 and 3, the same idea in different forms is embodied in the remaining figures. Thus in Fig. 4, I have shown the rings 17 of the two terminals associated with condensers 22 of any suitable type.

In Fig. 5 the condenser action is secured 80 not by an independent disk, as in Figs. 2 and 3, but by a back plate 23 integral with the condenser ring 17'. The back plate may be further continued by a sleeve 24 surrounding the line 11 and spaced therefrom by an insulating bushing 25.

In Fig. 6 I have substituted for the sleeve 24 a second back plate 23 connected to the line but spaced from the plate 23 by an interposed di-electric 26 of any suitable sort. 90 In this figure I have indicated diagrammatically a connector clamp 27, which would be utilized in some form or other in all of the constructions to electrically connect the ground lead 11 to the gap terminal. At the terminal the ground line may take the form of a rod of sufficient mechanical strength, not only to support the disk 16, ring 17, and plate 18, but also to afford the means by which the terminal is supported 105 upon an associated insulator, bracket, or the like (not shown).

It is of course obvious that this automatic acceleration of the gap is due to the nature 110 of the current imposed on the line—that is to say high-frequency surges—and is in no way dependent upon alteration of physical conditions, as e. g., the presence of moisture at the gap.

As above mentioned, the spacing between 115 gap terminals has ordinarily been adjusted with relation to the reduced resistance at the gap due to moisture conditions. By making the di-electric disk 15 of porous or moisture-absorbent insulating material, it is possible 120 to make the gap spacing of the buttons 15 suitable for dry weather conditions, that is to say much closer than would be safe in the presence of moisture at the gap. Upon 125 the wetting of the di-electric 16 by moisture 130

at the gap, it becomes a conductor and has the effect of enlarging the terminal area to the full diameter of the ring 17. As is well known, the tendency to arc-over between large spheres is less than that between small spheres at the same setting. Consequently, the enlarged terminal area afforded by the wetted disk 16 compensates the lowered resistance at the gap by enlarging the conductive area of the terminals. The flux field under moisture conditions at the gap is substantially that indicated in the area 20 in Fig. 3, the lines of flux at 21 being absent—unless the excessive current be one of high frequency.

The terminal thus combines protection of the gap against lowered resistance under moisture conditions by automatically enlarging the terminal area, with automatic elimination of corona lag under dry weather conditions when subjected to high-frequency impulses. Of course the high-frequency impulses pass the gap without hesitation under moisture conditions, since corona lag is already eliminated by the enlarged terminal area afforded by the wetted disk 16.

The constructions illustrated are merely examples which embody my invention in practical form and are subject to various modifications without departing from what I claim as my invention.

I claim—

1. An arc gap terminal comprising a conductor connected to the line, a metallic ring surrounding but spaced from said conductor, and adjustable means for increasing the condenser effect of said ring.

2. An arc gap terminal comprising a conductor connected to the line, a metallic ring surrounding but spaced from said conductor, and a metallic element connected to the line and spaced from said ring to increase the condenser effect thereof.

3. An arc gap terminal comprising a conductor connected to the line, a metallic ring surrounding but spaced from said conductor, and an adjustable metallic plate spaced from said ring to increase the condenser effect thereof.

50 4. An arc gap terminal comprising a conductor connected to the line, a metallic ring surrounding but spaced from said conductor, and a metallic plate connected to the line but spaced from said ring to increase the condenser effect thereof.

55 5. An arc gap terminal comprising a con-

ductor connected to the line, a metallic ring surrounding but spaced from said conductor, and a metallic plate connected to the line but spaced from said ring to increase the condenser effect thereof, said plate being adjustable toward or from the ring.

6. An arc gap terminal comprising a conductor connected to the line, a moisture absorbent insulator surrounding the same, a metallic ring carried by said insulator, and means for increasing the condenser effect of said ring.

7. An arc gap terminal comprising a terminal conductor connected to the line, a moisture absorbent insulator associated with said terminal conductor and serving to increase the effective conductor area of the terminal under moisture conditions at the gap, a metallic ring associated with said insulator and spaced thereby from the terminal conductor, and means for varying the condenser action of said ring.

8. An arc gap installation comprising a pair of spaced gap terminals in combination with a pair of condenser plates arranged respectively back of the gap terminals but movable toward and from the latter to adjust the break-down rating of the gap for high frequency current.

9. An arc gap installation comprising a pair of spaced gap terminal conductors, porous insulation associated with said terminal conductors and serving to increase the effective conductor area of the terminals under moisture conditions at the gap, together with condenser elements associated with the terminals, and means for varying the condenser effect of said condenser elements to vary the break-down rating of the gap for high frequency current.

10. An arc gap installation comprising a pair of spaced gap terminal conductors, porous insulation associated with said terminal conductors and serving to increase the effective conductor area of the terminals under moisture conditions at the gap, a metallic member surrounding said insulation and spaced thereby from the terminal conductor, together with condenser elements associated with the terminals, and means for varying the condenser effect of said condenser elements to vary the break-down rating of the gap for high frequency current.

In testimony whereof I have signed my name to this specification.

CHARLES E. BENNETT.
